WET BULB THERMOMETER

Charles W. Peterson, West Roxbury, Mass., assignor to B. F. Sturtevant Company, Hyde Park, Boston, Mass.

Application September 24, 1938, Serial No. 231,457

3 Claims. (Cl. 297—2)

This invention relates to wet bulb thermostats and relates more particularly to thermostats for use in passenger vehicles for converting air washer systems for air conditioning, from refrigerative cooling to evaporative cooling cycles when the wet bulb temperature of the outdoor air is low enough for evaporative cooling to be effective.

The ordinary wet bulb thermostat consists of a thermometer with the upper portion of a wick around its bulb, the lower portion of the wick lying a pool of water. The water is supposed to climb up the wick through capillary action. Differential thermostats including a dry bulb thermostat which adjusts a hygrostat to cause it to respond to wet bulb temperatures have also been used. Such thermostats have not proved entirely satisfactory for railway car service due to the difficulty of keeping the wick clean and of supplying clean water to the wick type, and to the difficulty of maintaining the adjustment of the differential type.

In some embodiment of the present invention, a thermometer has its bulb in a leather boot. A chamber in the thermostat body is arranged to receive water which is circulated through same at about one gallon per minute. The leather boot is connected to this chamber to receive an amount of water equal to that which is evaporated from its outer surface, the excess being by-passed back to the source. This new form of thermostat has functioned satisfactorily and accurately over a considerable period of time in railway passenger cars without requiring any attention whatever.

An object of the invention is to provide an accurate, rugged wet bulb thermostat.

The invention will now be described with reference to the drawing, of which:

Fig. 1 is a profile view of one embodiment of a wet bulb thermostat incorporating features of this invention, showing a drip basin below same;

Fig. 2 is a profile view of the thermostat of Fig. 1, with the thermostat body shown in section, and

Fig. 3 is a plan view looking downwardly upon the thermostat of Figs. 1 and 2.

The thermostat body 5 contains the chamber 6 which is provided for maintaining the proper water level in the device. The chamber 6 receives water under slight pressure through the inlet 7. A portion of this water passes through the passage 8 and enters a second chamber 9. The threaded pipe 10 of the special refrigeration fitting 11 is screwed into the lower portion of the chamber 9. The refrigeration nut 12 is fitted

onto the lower portion of the fitting 11 and secures the upper end of the leather boot 13 in tight contact within the nut so that it is water tight.

The boot 13 in one embodiment of the invention is of tanned sheepskin of uniform density and thickness to ensure uniform wetting through its entire surface.

The thermometer 14 extends through the compression nut 16, the chamber 9 and into the boot 13 with its bulb 15 near the lower end of the boot. The compression nut 16 is threaded into the thermostat body 5 to hold the thermometer securely in place.

The pipe plug 17 closes the upper portion of the chamber 6.

The funnel-shaped drip basin 18 is mounted below the boot to receive water dripping therefrom and the water is drained to the tracks through the pipe 19.

The bracket 20 is provided for mounting the thermostat in the outdoor air inlet passage.

In operation, a pump circulates water through the inlet 7 into the chamber 6 and out the outlet 4. The outlet 4 is located above the passage 8 so that the water level in the chamber 6 is always above the passage 8 ensuring that at all times, the boot 13 will be full of water.

It is preferred that no pressure be exerted by the pump, etc., upon the water in the boot 30 and that the only pressure be that from the water head in the boot and in the chamber 9. This is sufficient to cause the water within the boot to pass to its exterior, so that it may be evaporated by the air passing over it, and is insufficient to force any appreciable excess of water through the boot.

The stem of the thermometer 14 may be provided with the usual electric contacts (not shown) for actuating electric circuits for converting the associated air washer system from evaporative cooling to refrigerative cooling when the wet bulb temperature of the outdoor air rises above a predetermined point, and for converting the system from refrigerative cooling to evaporative cooling when the wet bulb temperature of the air falls below the predetermined point.

Water from the main spray line is usually supplied to the thermostat and in such cases it is necessary to provide a pressure regulating valve in the tubing connecting with the inlet 7 to reduce the pressure of the water entering the chamber 6. When pressure reducing valves are employed, it is desirable to provide an orifice in the inlet or in the tubing connecting with this 55

inlet for providing sufficient resistance to water flow to cause a momentary pressure to be built up in the reducing valve for dislodging any particle of foreign matter which may become lodged under its diaphragm.

While it is preferred that the chambers 6 and 9 be in the thermostat body, they could be in separate bodies and connected together by tubing corresponding to the orifice 8. Their purpose is to supply an excess of water to the thermometer element and to by-pass or discharge the excess of water over that required to replace the volume evaporated at the outer surface of the boot and they could accomplish this whether included in the same or separate bodies.

The thermostat may of course be used for reading wet bulb temperatures as well as for actuating controls and may be mounted in recirculated or conditioned air streams as well as in outdoor air streams.

While tanned sheep skin has been successfully used for the boot of the thermostat, other porous materials may be used. The term "boot" is defined herein as a porous receptacle for a thermometer or thermostatic element.

While one embodiment of the invention has been described for the purpose of illustration, it should be understood that the invention is not to be limited to the exact apparatus and arrangement of apparatus described, as many departures and modifications may be suggested to those skilled in the art, without departure from the spirit of the invention.

What is claimed is:

1. A wet bulb thermostat comprising a body having a relatively large chamber with substantially vertical walls, one of said walls having a substantially horizontal extension, said extension having an aperture with substantially vertical walls for receiving a thermostatic element and having an aperture with substantially horizontal walls connecting said first mentioned aperture and said chamber through said one wall, means forming a water inlet into said chamber below said horizontal aperture, a porous boot attached to said extension below said second mentioned aperture and in alignment with said first mentioned aperture, a thermostatic element extending through said first mentioned aperture into said boot, and means forming a water outlet

from said chamber above said second mentioned aperture.

2. A wet bulb thermostat comprising a body having a relatively large chamber with substantially vertical walls, one of said walls having a substantially horizontal extension, said extension having an aperture with substantially vertical walls for receiving a thermostatic element and having an aperture with substantially horizontal walls connecting said first mentioned aperture and said chamber through said one wall, means forming a substantially horizontal water inlet into said chamber below said second mentioned aperture, a porous boot attached to said extension below said second mentioned aperture and in alignment with said first mentioned aperture, a thermostatic element extending through said first mentioned aperture in said boot, and means forming a substantially horizontally extending water outlet from said chamber above said second mentioned aperture, said inlet and outlet extending through the opposite wall of said chamber to said one wall.

3. A wet bulb thermostat comprising a body having a relatively large tubular chamber with a substantially vertical axis and with substantially vertical walls, one of said walls having a substantially horizontal extension, said extension having an aperture with substantially vertical walls for receiving a thermostatic element and having an aperture with substantially horizontal walls connecting said first mentioned aperture and said chamber through said one wall, means forming a substantially horizontally extending water inlet into said chamber below said second mentioned aperture, a porous leather boot attached to said extension below said second mentioned aperture and in alignment with said first mentioned aperture, a thermostatic element extending through said first mentioned aperture into said boot, and means forming a substantially horizontally extending water outlet from said chamber above said second mentioned aperture, said inlet and outlet extending through the opposite wall of said chamber to said one wall, said horizontally extending aperture having a diameter substantially less than that of said outlet.

CHARLES W. PETERSON.
